UNITED STATES PATENT OFFICE.

URIAH G. POTTS, OF MARTINSBURG, WEST VIRGINIA.

RAIL.

No. 903,883.

Specification of Letters Patent.

Patented Nov. 17, 1908.

Application filed September 18, 1907. Serial No. 393,487.

To all whom it may concern:

Be it known that I, URIA G. POTTS, a resident of Martinsburg, in the county of Berkeley and State of West Virginia, have 5 invented a new and useful Improvement in Rails; and I do hereby declare the following to be a full, clear, and exact description thereof.

My invention relates to rails, and has special reference to the class of rails for use on railroads, traction roads, etc.

The object of my invention is to provide a rail which can easily and quickly be renewed in case of wear or breakage without disturbing a solid track, and one which will always be firm and rigid when in position and use.

My invention consists, generally stated, in the novel arrangement, construction and combination of parts, as hereinafter more 20 specifically set forth and described and particularly pointed out in the claims.

To enable others skilled in the art to which my invention appertains to construct and use my invention, I will describe the same 25 more fully, referring to the accompanying drawing, in which:—

Figure 1 is a cross-section of a track employing my improved rail. Fig. 2 is a longitudinal section of a track showing a side 30 elevation of the rail. Fig. 3 is an enlarged cross-section of the rail. Fig. 4 is a like view showing another form of the rail. Fig. 5 is an end view of another form of the supporting base. Fig. 6 is a cross-section of an 35 other form of base.

Like symbols of reference herein indicate like parts in each of the figures of the drawing.

As illustrated in the drawing, 1 represents 40 the base section of the improved rail, which is intended to be secured in position by being embedded in the concrete *a* or can be secured upon the ties of the road-bed according to any of the approved manners of securing 45 rails. The ends of each of the base sections 1 are cut square across, so that they will abut against each other when the rail is laid down in order that the rail may be built up in position without difficulty. The base flange 2 of the section 1 is of the usual shape and size, with the web 3 rising up from the same for some distance, and the upper end of said web is split or opened out to form a channel base 4, which thereby forms a space 5 and 55 the side-webs 6. This space or hollowed out portion 5 is intended to receive the tongue

or flange with which the tread section is supplied and the tops or upper ends of the webs 6 are rounded, as at 7, in order to conform to the under face of the upper part or head of 60 the tread section.

The tread section is shown at 8, and is provided with the tongue or flange 9 extending down from the head 10 thereof, which flange is of the size and shape to fit in and conform 65 to the space 5 in the channel base 4 of the base-section 1. These tread sections are cut square across at their ends, and the under faces 11 of the head portions rest against the rounded ends 7 on the webs 6.

When the tread sections 8 are set in position within the channel base 4 of the base sections 1, wedge shaped bolts or keys 12 are placed or driven within holes 13 and 14 formed in the webs 6 and tongue 9 respectively on the base sections and tread sections, and such keys are held in place by means of nuts 15 engaging with the ends of said keys. These keys 12 are provided with an inclined upper face for engaging with a like face in 80 the holes 13 on one of the webs 6 and with a like face in the holes 14 in the tongue 9, while a straight portion is formed on said keys for said nuts and for fitting in like holes in the other holes 13 in the other web 85 6, so that said arrangement will hold the two sections of the rail together in a solid and rigid manner by drawing the tongue downward and will prevent any movement of the sections or vibration or noise of one part 90 upon the other.

In laying the rails 1 for forming a track such as is shown in Fig. 1, a tie-beam 16 extends between such rails, being connected to the web 3 of the base sections 1 by means of 95 bolts 17 passing through said web and through flanges 18 on said beam, and such beam is embedded in the concrete *a* around the rails.

In the use of the rails for traction purposes, the inner web 6 on the base sections 1 is provided with an inwardly projecting flange 19 for forming a girder rail to act as a vehicle track on each side of the rails, as shown in Figs. 1, 2 and 3, and if desired the space 100 5 in the channel base 4 of the section 1 can be provided with the inclined sides 20 on the webs 6 of the same, with which inclined sides 21 on the tongue 9 of the tread section 8 can engage in order to form a wedging action 105 110 when the treads are placed in position within the base sections, as is shown in Fig. 4.

The base section 1 can also be provided with a track flange 19 on both sides of the webs 6 on the same to form a double girder rail, as shown in Fig. 5 and the space 5 can extend entirely through the web 3 of the base section 1, as shown in Fig. 6. It will thus be seen that the sections of my improved rail are of such a shape and form that they may be rolled in an ordinary rolling mill, and thus produced without any unnecessary or additional cost, and when so produced and properly perforated to receive the wedge-bolts, they can be readily laid upon the road-bed and secured thereon as may be desired. The base sections may be made of cheaper metal than the tread sections as the latter alone are subjected to being worn or damaged by the contact of the traveling wheels therewith. The tread sections are made to break joints with the joints in the base sections if desired, and when they are finally bolted to place the rail is quite as rigid, firm and secure at all points as if made in a single piece, and this, of course, will occur throughout the entire length of the rail construction. The concrete *a* can be provided with the reënforcing rods *b* through the same, and when such concrete is shaped like that shown in Fig. 4, it can carry a derailed car along the same in safety. The base sections are not required to be removed from the road-bed, and will seldom need repaving, as they will not be liable to breakage, while any of the tread sections may be removed and replaced when necessary, and any such section when removed may be cut and replaced in divisions, if desired, it being only necessary to have the holes properly punched through the flange and properly spaced. It will thus be obvious that the rail may easily and quickly be repaired upon the

road, as all the joints are of extreme simplicity and will not get out of order.

What I claim as my invention, and desire to secure by Letters Patent, is:—

1. A rail having a base section formed with a channel web and a girder flange extending out from said web, a tread section having a tongue fitting within said web, and wedge-shaped bolts passing through inclined faced holes in one of said web portions and tongue and through a straight hole in the other web portion by a straight portion thereon, for holding said base and tread sections in place.

2. A rail having a base section formed with a channel web having inclined interior sides, a tread section having an inclined sided tongue fitting within said web, and wedge-shaped bolts passing through inclined faced holes in one of said web portions and tongue and through a straight hole in the other web portion by a straight portion thereon, for holding said base and tread sections in place.

3. A rail having a base section formed with a channel web having inclined interior sides and a girder flange extending out from said web, a tread section having an inclined sided tongue fitting within said web, and wedge-shaped bolts passing through inclined faced holes in one of said web portions and tongue and through a straight hole in the other web portion by a straight portion thereon, for holding said base and tread sections in place.

In testimony whereof, I the said URIAH G. POTTS, have hereunto set my hand.

URIAH G. POTTS.
